UNITED STATES PATENT OFFICE.

JOHN E. BOLLING, OF CHICAGO, AND ERNEST SZEKELY, OF EVANSTON, ILLINOIS,
ASSIGNORS OF THREE-FOURTHS TO DRYING SYSTEMS, INC., OF CHICAGO, ILLINOIS,
A CORPORATION OF ILLINOIS, AND ONE-FOURTH TO ERNEST SZEKELY.

AIR HEATER.

Application filed July 26, 1926. Serial No. 124,957.

The main objects of this invention are to provide a more efficient fluid heater particularly for heating large quantities of air to high temperatures; to provide a simple, self-contained, economical light-weight welded or lock-seamed sheet metal construction; to provide an air heater having true counter-flow between the air and the combustion gases; to provide a more suitable arrangement of flues for accelerating the heat interchange; to provide a heater having the combustion tube and the flue tubes integrally joined into a composite unit which is then freely supported in the heater casing to allow movement for thermal expansion and contraction; to provide an improved form of combustion tube adapted to withstand the high combustion temperatures; to provide means for evenly distributing the air to be heated around the combustion tube in order to prevent uneven circulation, and uneven heating of the tube, and for improving the fuel combustion; to provide a furnace in which all of the passages, and especially the flue gas passages, are accessible for cleaning; to provide a heater unit which is adaptable to be connected into batteries with a saving in the amount of air duct piping required and also to reduce heat losses and the amount of space occupied.

In the prior devices substantially no attempt was made to obtain uniform, evenly distributed air circulation throughout the furnace. This resulted in low efficiency and caused portions of the furnace to become overheated. The overheated spots disturbed the air circulation and caused the destruction of the furnace by melting down the adjoining metal walls.

In this invention the outer shell or envelope is rectangular in form and is built up of panels of heat resisting material encased in sheet metal. The combustion chamber and flue gas structures are suspended in the envelope with freedom to move under expansion. The combustion chamber is a cylindrical sheet metal tube provided with longitudinal fins on the outside, and is enclosed by a larger tube which forms uniform peripheral air spaces and serves to confine the air to circulate closely to the walls of the com-

bustion tube. The gas passage ducts are joined to the rear end of the combustion tube, eliminating the customary flue sheets. The gas flues comprise a pair of parallel flat ducts which extend forwardly over the top of the combustion tube, and then upwardly and back to the rear end of the outer envelope, where they are connected into ducts leading to the stack.

Transverse baffle sheets are provided under the lower pair of ducts and between the upper and lower pairs. The baffles direct the air, which enters at the upper rear end of the furnace, forwardly around and between the upper pair of ducts, then down and rearwardly in contact with the lower pair of ducts, and again down and then forwardly through the baffled space around the combustion tube. The gas ducts are rectangular in cross section, considerably greater in width than in thickness, and the space around the ducts is uniform and quite narrow so that the air is also confined close to the surface of the ducts.

The discharge ends of the gas ducts are reduced in width because the flue gases are cooled and reduced in volume by the entering air. Also vertical baffle plates are provided at the sides of the reduced ends, which extend parallel to the converging sides of the upper ducts, and then flare outwardly to form a Venturi constriction for reducing the resistance to the incoming air. The flaring ends also provide a small expansion chamber for the entering air in which the velocity is reduced and the pressure equalized to evenly distribute the air in entering the passages around the gas ducts.

The cross sectional area is increased as the air is heated in flowing along the upper pair of ducts to lessen the velocity along these cooler portions of the ducts in proportion to the slower rate of heat interchange. At the forward end of the upper ducts the air flows down and back along the surfaces of the lower pair, and then down into a second enlarged chamber at the rear of the combustion tube which causes the air to be distributed evenly around the combustion tubes.

The space around the lower pair of ducts is held substantially uniform. The air con-

tinues to expand and consequently increases in velocity in approximate proportion to the increase in the rate of heat interchanged along the hotter portions of the lower ducts. 5 This arrangement accordingly increases the cooling of the lower ducts and maintains the upper and lower reaches more nearly at the same temperature and prevents overheating in the lower portions, which are adjacent to the extremely high temperatures in the combustion tube.

The cross sectional area around the combustion tube is not greatly increased and consequently the expansion from the combustion temperatures causes the air to flow at very high velocities. This prevents the combustion tube from being melted.

The baffle fins in the space between the combustion tube and the enclosing tube prevent 20 the air from the lower side from rising to the upper side; and maintains a more equal distribution. Since the air is confined to longitudinal passages along the tube, the higher temperature at the upper side causes greater 25 velocities and results in an increase in the amount of cooling. Consequently the temperatures of the upper and lower portions of the tube are nearly equalized.

By more correctly proportioning the different parts of the furnace, as described, the efficiency of the heater unit is greatly increased. The maximum air flow and highest rates of combustion may be attained. The walls may be heated to the maximum safe 35 temperature throughout and destructive temperatures prevented.

The construction of the heater unit is such that the heated air may be conducted out through the top of the outer shell or out 40 through either side. The front end of the furnace is suitably apertured at the top and sides to receive fittings which may be closures or which may provide apertures for receiving the ends of the communicating ducts, as may be desired. This permits standardizing a 45 single type of heater unit which is adaptable to be used interchangeably in nearly all classes of installations.

The apertures at the sides are also adapted 50 for receiving short rectangular tubes for connecting the units in batteries and drawing the heated air out through a single duct at one end. This reduces the overhead space required and effects a large economy in the 55 amount of necessary piping.

In this invention, the combustion chamber, 60 which is a sheet metal tube disposed in a horizontal plane and the combustion gas flues are joined into an integral construction which is 65 flexibly sustained in the heater casing with the combustion tube extending loosely through the casing and slidably fitted in the casing opening. The oil burner nozzle is mounted in the open end of the combustion 70 tube, and the terminus of the flue tubes ex-

tends slidably through the end wall of the casing, so that the structure forming the combustion gas passages is continuous. The entire outer surface of the metal walls in contact with the burning gases is exposed to the circulating air and is available for useful heat transmission. Leakage is avoided, vertical flue sheets are eliminated, and cracking or breaking at the joints is avoided by allowing freedom for the thermal volumetric 75 changes in the metal.

Also, the greater part of the heat interchange is caused to take place around the combustion tube, which is made of a chrome steel alloy which is especially capable of withstanding the high temperatures. The tube is built up of segmental marginally flanged strips welded together in a suitable manner. The combustion tube extends through a tube 85 in the casing which bears on the outer edges of the flanges.

An illustrative embodiment of this invention is shown in the accompanying drawings, in which:

Figure 1 is a perspective view of the heater with parts broken away and with the casing shown in broken lines.

Fig. 2 is a vertical section on the longitudinal axis of Fig. 1.

Fig. 3 is a section taken on the line 3—3 of Fig. 2.

Fig. 4 is taken on the line 4—4 of Fig. 2.

Fig. 5 is a front elevation of the heater with a portion broken away.

Fig. 6 is a section on the line 6—6 of Fig. 3.

Fig. 7 is a fragmentary detail of one end of the combustion tube.

Fig. 8 is a fragmental plan view of a battery of heaters.

Fig. 9 is taken on line 9—9 of Fig. 8.

Fig. 10 is a perspective view of the front end of the heater casing.

Figs. 11, 12, 13, 14 and 15 show different types of fittings for the front end of the casing shown in Fig. 10.

Referring to the drawings, the shell or envelope 1 of the heater is preferably built up of insulating walls comprising a thickness of non-conducting material 2 encased between the sheet metal walls 3. In arrangement, the outer shell 1 comprises a long rectangular chamber 4, rounded at the bottom, and a narrower rectangular chamber 5 in front of the chamber 4 and connecting therewith through the circular opening 5^a. An air inlet port 6 is provided at the rear at the upper wall of the casing, and the air is drawn out or forced out through an upper opening 7 in the chamber 5, or through side openings 8 when the heaters are arranged side by side. A baffle plate or horizontal partition 9 extends from the dividing wall between the chambers 4 and 5 above the opening 5^a, toward the rear of the casing, and the second baffle plate 10 is located above the baffle 9, and extends from

the rear wall of the casing, forwardly. An air tube 11 is fixedly mounted in the casing and extends from the opening 5 rearwardly.

The structure for the flue gases comprises a horizontally disposed combustion or firing tube 12, and the flue ducts 13 which form a continuation of the combustion tube 12, and are doubled back over the combustion tube between the baffle plates 9 and 10, and then extend rearwardly above the upper baffle 10 to the stack outlet 14, at the rear of the casing. The flue tubes 13 are of a flat rectangular construction arranged and connected to form double channels with spaces between the tubes. At the rear end, the upper flue tubes are reduced in width so that the air can circulate between the two upper tubes, and so that the area of the flue passes is reduced approximately in accordance with the diminishing volume of the cooling gases. This reduction in flue area affords a two-fold advantage. It insures a uniformly high rate of transmission and renders it difficult to burn an excess quantity of fuel.

The oil burner nozzle 15 is mounted in a casting 16 which is supported within the tube 16 which is joined to the front end of the combustion tube 12, as shown in Fig. 2. Oil is sprayed from the nozzle 15 directly into the tube 12 and the combustion takes place along the length of the tube at very high temperatures.

The air enters through the port 6, passes forwardly above the upper baffle 10, circulating around and between the upper flue tubes, downwardly between the forward end of the baffle 10, rearwardly through the space between the upper and lower baffle plates, then downwardly and forwardly around the periphery of the combustion tube 12 and then leaves the casing from the chamber 5. The outer end or terminus 16 of the flue tubes is slidably supported, and the weight of the bank of flues is flexibly suspended from the top wall of the casing 1 by means of suitable supports 17. The combustion tube is provided with outer longitudinal ribs or flanges 18 which form a plurality of narrow passages in the space between the tube 12 and the enclosing tube 11. The baffles or flanges 18 thereby evenly distribute the flow of air around the heated tube 12 and prevent stratification or uneven circulation.

The tube 12 is built up of channel shaped strips 19 having the outwardly extending flanges 18. The abutting flanges are welded in a line along the length of the tube, preferably near the bottom of the flanges. Since the flanges or ribs are integral with the wall of the tube 12, the heat transmission is much greater than is obtainable with non-integral extended surfaces.

The sides of the upper pair of gas ducts 13 are tapered inwardly as shown in Fig. 3 and vertical baffle walls 31 are provided at

the sides of the upper ducts, between the upper horizontal plate 10 and the top of the shell 1. The walls 31 extend parallel to the sides of the ducts and then flare outwardly at the rear end to form the Venturi 70 restriction 32 and the expansion chamber 33.

In this construction all parts of the heater are readily accessible for inspection and cleaning. The stack may be disconnected at 14 to afford access to the upper layer of flues. 75 The lower flues are accessible through a port in the rear end of the furnace, which is normally closed by the cover 21; and the chamber 5 may be reached by removing the side closures. 80

When the heaters are installed side by side in a battery formation, it is especially desirable to be able to remove any one of the units without disturbing the remaining units. Accordingly, recesses 22 are formed in the side 85 of the front end of the outer shell 1. The recesses are open at the front and at the top, and the short rectangular connecting tubes 23 may be inserted after the units are in place. The tubes 23 are then secured by 90 means of the flat straps 24, which engage with the front wall of the units at the lower end and extend over the front and across the top where the straps 24 are secured by the bolts 25. Preferably the straps are wider 95 than the connecting tubes 23 and cover the joints between the tubes and the adjoining units. When it is desired to remove a certain unit the straps are loosened and the connecting tubes 23 withdrawn. Then the unit 100 may be removed forwardly without disturbing the remaining units.

When it is desired to entirely close the side, as at the right side of Figure 8, a plane insulating panel 25 is inserted in the recess 105 22 and held in place by an angular strap 26. A side outlet is shown at the left side of Fig. 8. The tube 27 is inserted in a suitable orificed side panel 28, which is secured in the recess 22 of the end unit in the same manner 110 that the closure 25 is secured. The outlet tube 27 may also be used in the top outlet aperture 7, or the aperture 7 may be closed by the cover 29. The cover member 29 is constructed with a flange 30, which is adapted 115 to project under the edges of the closure strap 23 or 26, as the case may be. In this manner one standardized feature unit is provided which may be assembled in any suitable manner to suit the requirements of the particular 120 installation.

In operation, the air is continuously circulated through the casing around the flues in true counter-flow relation to the heated gases, and then out through the outlet chamber 5. 125 In passing along the combustion tube the air is evenly distributed close to the tube, so that the greater part of the heat interchange takes place around the flaming gases. The maximum temperature of the tube may be 130

maintained without burning the tube in spots. When the tube is raised to a red heat or a white heat, although the metal is not destroyed, there is a tendency for sagging since the metal becomes weaker. By providing the longitudinal flanges, the walls of the tube are well supported and the useful life of the tube is lengthened. The flanges also materially increase the radiating surface, especially where the flanges are integral with the tube walls, as shown.

While but one specific embodiment of this invention has been herein shown and described, it is to be understood that numerous details of the construction shown may be altered or omitted without departing from the spirit of this invention, as defined by the following claims.

We claim:

- 20 1. In an air heater, a combustion tube for burning fuel, said tube comprising a plurality of longitudinal segmental strips having marginal flanges projecting outwardly, said strips joined at the edges.
- 25 2. In an air heater, a casing, an air tube mounted in said casing, a combustion tube having a plurality of longitudinal outwardly projecting ridges, said combustion tube being supported in the air tube by said ridges and unrestrained for longitudinal thermal expansion and contraction.
- 30 3. In an air heater, a casing having an upper outlet, a combustion chamber in the lower part of the casing, flat flue tubes extending back over the top of the combustion chamber and then forwardly at the top of the casing to said outlet, said flue tubes forming a continuous passage from the combustion chamber to said outlet, said casing having an air inlet near said outlet, and baffles across the chamber for directing the air.
- 35 4. In a fluid heater a combustion tube, horizontally flat flue tubes arranged in reversely extending layers above the combustion tube and forming a continuous passage therefrom, means for oppositely directing the fluid along

the successive layers of the tubes and then along the combustion tube.

5. In a fluid heater, a casing, a horizontal combustion tube, flue tubes arranged in reversely extending layers above the combustion tube and forming a continuous combustion gas passage therefrom, said combustion tube and flue tubes being integrally connected, means for suspending the flue tubes in the casing and a support for the combustion tube.

6. In a fluid heater, an outer envelope of heat insulating material having ports and baffles for directing the fluid to be heated through the heater, a sheet metal firing tube, and continuous sheet metal combustion gas ducts folded back and forth in layers above the firing tube and joined thereto to form an integral structure, said structure flexibly supported in the envelope for heating the fluid.

7. In combination, a plurality of heater units each having apertures in the adjacent sides, and having flanges around two adjacent sides of said apertures, the units being arranged so that the relatively adjacent flanges are in abutment, tubes removably inserted in the recesses formed by the abutting flanges, and a strap attached to the heater units for covering the joints and holding the tubes in place, said straps extending over the two edges of the tubes opposite to the flanges.

8. In combination in an air heater a shell having an aperture, and having flanges around two adjacent sides of the aperture, a panel inserted in the recess formed by the flanges for closing the aperture, and an angular section strap extending over the two edges of the panel opposite the flanges and covering the joints between the panel and the shell, the strap being secured to the shell for holding said panel.

Signed at Chicago this 24th day of June, 1926.

JOHN E. BOLLING.
ERNEST SZEKELY.
